UNITED STATES PATENT OFFICE

108,876

DESIGN FOR A BUILDING

John Donovan, Decatur, Ill.

Application October 25, 1937, Serial No. 72,429

Term of patent 7 years

To all whom it may concern:

Be it known that I, John Donovan, a citizen of the United States, residing at Decatur, in the county of Macon and State of Illinois, have invented a new, original, and ornamental Design for a Building, of which the following is a specification, reference being had to the accompanying drawing, forming part thereof.

Figure 1 is a perspective of a building, showing my new design;

Figure 2, a top plan view, and
Figure 3 an elevation of the right hand end of
Figure 2.

The awning shown in Fig. 1 has been omitted
from Figs. 2 and 3 for convenience of illustration.

I claim:

The ornamental design for a building as shown
and described.

JOHN DONOVAN.
